Inventor,

Robert Elliott.

United States Patent Office.

ROBERT ELLIOTT, OF CHESTER, PENNSYLVANIA.

Letters Patent No. 77,180, dated April 28, 1868.

IMPROVED RAILWAY-RAIL SPLICE.

The Schedule referred to in these Letters Patent and making part of the same.

TO ALL WHOM IT MAY CONCERN:

Be it known that I, ROBERT ELLIOTT, of the city of Chester, county of Delaware, and State of Pennsylvania, have invented a new and useful Device for Joining Railroad-Rails; and I do hereby declare that the following is a full and exact description of the same, reference being had to the annexed drawings, forming part hereof, and to the several letters marked thereon, in which drawings—

Figure 1 is an elevation of the cross-tie, and also of the outside of two railroad-rails as joined by my said device.

Figure 2 is a transverse vertical section of the cross-tie, and an elevation of the inside of said rails as joined by my said device.

Figure 3 is a transverse vertical section of the cross-tie, and of a rail, and of my device as applied thereto.

My device is intended to take the place of what is generally known amongst railroad-constructors as a "joint-block."

I denominate my said device a railroad-rail joiner. It consists of wrought-iron flanged plates, formed as hereinafter described, and applied both to the inside and outside of the rails of a railroad, so as to overlap the joint or point where two contiguous rails meet, the whole being firmly bound together by bolts and burrs, which latter are secured in their places by guard-plates, as hereinafter described:

To enable others skilled in the art to make and use my invention, I will proceed to describe its construction and mode of operation, similar letters being employed to designate corresponding parts in the several views.

In the drawings, A and B represent two railroad-rails, the ends of which meet at a. C is the cross-tie. These parts are in the ordinary form. D is a double plate of wrought iron, overlapping the joint a on the outside of the rails A and B, and having two flanges, e and e', one of which, e, projects underneath the rails between them and the cross-tie, and the other, e', projects outwardly, and rests upon the cross-tie C, to which it is spiked, as shown in fig. 3. E is a double plate of wrought iron, similar to the plate D, overlapping the joint a on the inside of the rails A and B, and having two flanges, d and d', one of which, d, projects underneath the rails, between them and the cross-tie, and the other, d', projects outwardly, and rests upon the cross-tie C, to which it is spiked, as shown in fig. 3. The plates D and E are curved or arched, so as to conform to the shape of the sides of the rails, as shown in fig. 3. F is an iron bolt, which is passed through the plates and rail, as shown in fig. 3. f is the head of the bolt. g is a burr, screwed on the end of the bolt. h is a washer, interposed between the burr g and plate E. G is a plate of sheet iron, which has apertures in it to correspond with the burrs employed, the plate G being turned down over the burrs, so that the latter fit into the apertures, as shown in fig. 3, the burr being thus prevented from turning and working off of the bolt. H is also a plate of sheet iron, which is turned down over the heads of the bolts, as shown in fig. 3, to prevent the bolt from working out of place.

While the plates D and E are being applied to the rails, the guard-plates G and H stand upright until the bolt and burr are adjusted, when said plates are turned down, so as to guard both bolt-head and burr, as represented in fig. 3.

It is not necessary that the apertures formed in the plate G should conform exactly to the shape and size of the burrs, provided these apertures fit the burrs nearly enough to prevent them from turning when this plate is in its proper place.

I prefer to make each of the two plates D and E of a single sheet of $\frac{3}{8}$ three-eighths of an inch thick wrought iron doubled, and doubled over again at the top, as shown in fig. 3, to secure strength. Two separate sheets, however, might be united, and bent over at the top, in the same manner as I have just described, and sheets of a greater or less thickness than $\frac{3}{8}$ three-eighths of an inch might be employed if desired.

The guard-plates G and H may be of $\frac{1}{8}$ one-eighth inch thick sheet iron, so as to be easily worked.

Having thus described my invention, I claim, and desire to secure by Letters Patent—

1. The railroad-rail joiner, composed of the double-flanged plates D and E, of wrought iron, the bolt F, burr g, and guards G and H, all constructed substantially as set forth.

2. The guard H, overlapping a series of two or more projecting bolt-heads, f, to prevent the bolts F from working out of their places in case of the accidental removal of some of the burrs g.

ROBERT ELLIOTT.
